Des. 222,797
Patented Jan. 4, 1972

222,797

HANDLE GRIP

Archie R. Fine, 2319 Judith 83705, and Charles T. Poin-
dexter, 4023 Whitehead 83703, both of Boise, Idaho

Filed Feb. 25, 1970, Ser. No. 21,606

Term of patent 14 years

Int. Cl. D8—07; D12—16
U.S. Cl. D8—107

FIG. 1

FIG. 2

FIG. 3

FIG. 1 is a top left perspective view of the handle grip embodying our new design;

FIG. 2 is a bottom right perspective view;

FIG. 3 is an end elevational view thereof, in use;

FIG. 4 is a side elevational view thereof, in use; and

FIG. 5 is a side elevational view of the handle grip with the figure drawn in dotted lines for illustrative purposes.

The handle shown in broken lines in FIGS. 3 and 4 is shown for illustrative purposes only.

We claim:

The ornamental design for a handle grip, substantially as shown and described.
